GUY H. RAYBURN, OF COLUMBUS, OHIO, ASSIGNOR OF ONE-HALF TO
STRAFFORD R. HEWITT, OF COLUMBUS, OHIO.

MOLDER'S FLASK.

No. 842,700.

Specification of Letters Patent.

Patented Jan. 29, 1907.

Application filed August 11, 1906. Serial No. 330,211.

To all whom it may concern:

Be it known that I, GUY H. RAYBURN, a citizen of the United States, and a resident of Columbus, in the county of Franklin and State of Ohio, have invented a new and Improved Molder's Flask, of which the following is a full, clear, and exact description.

This invention is an improved molder's flask, having among other objects to provide a device of this character in which the impression in the sand of the desired article to be cast may be expeditiously and perfectly formed.

With this in view the invention consists of a cope and a drag capable of being opened laterally, combined with a pattern-board adapted to form a partition therebetween, the whole being provided with effective means for holding them in perfect register or for holding the cope and drag in register only.

Reference is to be had to the accompanying drawings, forming a part of this specification, in which similar characters of reference indicate corresponding parts in all the figures.

Figure 1 is a perspective view of the flask complete. Fig. 2 is a rear side elevation of the same. Fig. 3 is a transverse central vertical section. Fig. 4 is a plan view of the cope, the same being shown laterally opened; and Fig. 5 is a transverse section through the pattern-board.

Referring to the drawing figures, the numeral 1 indicates a rectangular frame forming the drag for the flask. At opposite diagonal corners of the frame ribbed corner-plates 2 are provided, reinforcing and strengthening the drag at these points. A hinge 3 is secured at a third corner of the drag, adapting it to be laterally separated when desired to remove the sand therefrom. For securely holding the hinged portions of the drag together when same is in use is provided at the corner diagonally opposite a clamp comprising a plate 4, having a hooked end, and a plate 5, having an enlarged rounded end adapted to be engaged by the hook and held in engagement therewith by a lever 6, pivoted in a bifurcation of the plate 5 and having projections 7 extending at its sides, designed to pass around the hooked end of the plate 4, as clearly shown in Fig. 1.

At each end of the drag is secured a washer 8, provided with a projecting stud 9, on

which is journaled a guide-bar 10, having 55 projecting from its inner face a lug 11, seated in a recess in the washer when the guide-bar is extended in a vertical direction. A thumb-nut 12 is threaded on the outer end of the stud 9 and is designed to hold the guide-bar 60 locked in either vertical or horizontal position. At the top rear edge of the drag is rigidly fixed extending hinge members 13, fashioned in the shape of upwardly-extending hooks. These coöperate with hinge 65 members 14, secured to the lower edge of a partition 15, forming a pattern-board for the flask. As shown in Fig. 2, the hinge members 14 are substantially spool-shaped and may be vertically lifted out of the hinge 70 members 13 or rotated therein, as desired. To the opposite face of the pattern-board 15 hooked hinge members 13^a, in alinement with the hinge members 13 and of the same construction, are secured.

75 16 indicates brackets fixed to the ends of the pattern-board alining with the guide-bars 10 when the latter are in vertical position and having adjustable sockets 17 fitting in grooves in the brackets and held in adjusted position by the bolts shown. A plate 18, fixed to the lower face of the pattern-board, has fixed to it, preferably as an integral part thereof, a pin 19, which when the pattern-board and drag are assembled passes through 80 an apertured plate 20, secured to the drag. An apertured plate 20^a, secured to the top face of the pattern-board in alinement with the plate 20, is of the same construction and performs a like function for a cope 21 when 90 in register with the top face of the pattern-board. The cope 21 is of the same construction as the drag 1, differing only in the particulars hereinafter noted.

95 The cope is constructed of a rectangular frame adapted to be diagonally divided by reason of a hinge 3^a, corresponding to the hinge 3 of the drag, and a clamp consisting of the parts 4^a, 5^a, and 6^a of the same construction as the parts 4, 5, and 6 of the drag, suitable corner-plates 2^a being also provided. Attached to each end of the cope in alinement with the guide-bars 10 are brackets 16^a and adjustable sockets 17^a of the same construction as the brackets and sockets of the 100 pattern-board and coöperate with the upper ends of the guide-bars in holding the parts 105 when assembled in exact register.

- To one of the bottom edges of the cope are secured spool-shaped hinge members 14^a, in alignment with and of the construction of the hinge members 14. Also secured to the bottom edge of the cope at that side opposite from the hinges is a plate 18^a, having fixed to it a pin 19^a, adapted to pass through the aperture in the plate 20^a when the cope and pattern-board are in register. By the construction of the fastenings between the drag and pattern-board and between the pattern-board and cope it is seen that the pattern-board can be removed and the cope and drag directly assembled and secured together in the same manner as are the pattern-board and drag. This construction admits of the flask being used in connection with the pattern-board or used as an ordinary flask consisting only of a cope and drag.
- As shown, the cope is preferably made slightly deeper than the drag and is provided with a series of inclined grooves 22 on its inner walls to prevent the sand from dropping out when moving the cope from place to place. The use of the improved flask in connection with the pattern-board will be found of special advantage in casting name-plates or other articles having projection of no considerable length. For making such a casting a pattern of the plate or other article is secured to that side of the pattern-board forming the bottom of the drag. Sand is then packed in the drag in the usual manner. The flask is then inverted and the cope packed with sand, after which the pattern-board having the pattern fixed thereon is removed and the cope and drag brought directly together, providing a mold ready for the casting operation.
- Ordinarily when the pattern-board is in use the guide-bars 10 are turned to a horizontal and inoperative position, the members of the flask being separated from each other by revolving them about their hinged connection. Should, however, the pattern-

board be dispensed with, the guide-bars 10 are set vertically, adapting the flask to be used as an ordinary snap-flask.

Although I have particularly described the invention in detail, it is to be understood that the scope thereof is limited by the annexed claims only.

Having thus described my invention, I claim as new and desire to secure by Letters Patent—

1. A molder's flask comprising a cope and a drag hingedly connected at their corners whereby they may be laterally opened, guide-bars pivotally attached to the ends of the drag adapted to be locked in horizontal and vertical positions, adjustable sockets carried by the cope coöperating with the guide-bars, and hinge members secured to both the cope and drag adapting them to be vertically separated.

2. A molder's flask consisting of a cope made up of two members hingedly connected together, a clamp for holding the members of the cope from separation, a drag consisting of two members hinged together, a clamp for holding the members of the drag from separation, guide-bars for maintaining the cope and drag in register, and means whereby the guide-bars may be turned to operative and inoperative position.

3. In a molder's flask, a cope, a drag, guide-bars pivotally attached to the drag, means for locking the guide-bars in horizontal and vertical positions, brackets carried by the cope coöperating with the guide-bars, and adjustable sockets carried by the brackets for the purpose described.

In testimony whereof I have signed my name to this specification in the presence of two subscribing witnesses.

GUY H. RAYBURN.
